UNITED STATES PATENT OFFICE.

WILLARD C. LIPE AND JOHN W. COUGHTRY, OF SYRACUSE, NEW YORK; STELLA S. COUGHTRY ADMINISTRATRIX OF SAID JOHN W. COUGHTRY, DECEASED.

CIGAR-MAKING MACHINE.

1,134,469.

Specification of Letters Patent.

Patented Apr. 6, 1915.

Application filed November 16, 1906. Serial No. 343,762.

To all whom it may concern:

Be it known that we, WILLARD C. LIPE and JOHN W. COUGHTRY, of Syracuse, in the county of Onondaga and State of New York, have invented a certain new and useful 5 Cigar-Making Machine, of which the following is a specification.

Our invention has for its object the production of a cigar-making machine which is 10 particularly simple and economical in manufacture, and highly efficient and durable in use; and to this end it consists in the novel combinations and constructions hereinafter set forth and claimed.

15 In describing this invention, reference is had to the accompanying drawing in which like characters designate corresponding parts in all the views.

Figure 1 is a perspective view of one exemplification of our invention. Fig. 2 is a 20 sectional view, partly in elevation, of a portion of the machine. Fig. 3 is a plan of one side thereof, the hopper for such side being removed and indicated by dotted lines. Fig. 25 4 is a plan of one of the hoppers, and a contiguous supporting standard. Fig. 5 is a plan, partly broken away, of one of the 30 filler-conveyers, and a portion of its actuating means. Figs. 6 and 7 are sectional views, partly in elevation, on line A—A, Fig. 5, illustrating the filler-conveyer in different positions. Fig. 8 is a sectional view, 35 partly broken away, of the plunger of one of the filler-conveyers. Fig. 9 is a sectional view, on line B—B, Fig. 5. Figs. 10 and 40 11 are inverted plans of detached parts of said actuating means. Fig. 12 is a plan, parts being removed, of a rolling mechanism, a wrapper-controller, a binder-engaging means, and adjacent parts. Figs. 13 45 and 14 are elevations, partly broken away and in section, of the mechanism seen in Fig. 12, additional means being also shown. Figs. 15, 16, 17 and 18 are detail views illustrating the manner of rolling the binder and 50 wrapper about the filler. Fig. 19 is a sectional view, on line C—C, Fig. 13. Fig. 20 is a detail elevation, partly in section, of a portion of the actuating means for a rolling 55 mechanism and a wrapper-controller, and adjacent parts. Fig. 21 is an elevation of a part of a wrapper-controller. Fig. 22 is a plan, parts being removed, of the means for controlling the operation of some of the 60 mechanism of the machine, and a portion of

the frame. Fig. 23 is a sectional view, on line D—D, Fig. 22. Fig. 24 is an enlarged view, partly broken away, of a heading mechanism, and portions of the driving element and the frame. Figs. 25 and 26 are, 65 respectively, plan, and elevation, partly in section, of a part of the mechanism seen in Fig. 24. Fig. 27 is an elevation of a portion of a heading mechanism, and contiguous parts. Figs. 28 and 29 are enlarged detail 70 elevations, partly in section, of a thimble, and coacting parts. Figs. 30 and 31 are opposing face views, partly broken away, of the sections of said thimble, and adjacent parts. Figs. 32 and 33 are sectional 75 views, partly in elevation, on line E—E, Fig. 24, looking in opposite directions. Fig. 34 is a sectional view, on line F—F, Fig. 33. Fig. 35 is a detail elevation, partly in section, of portions of a heading mechanism 80 and the frame. Fig. 36 is a sectional view, partly in elevation, on line G—G, Fig. 3. Fig. 37 is an elevation, partly in section, of a portion of the means for controlling the 85 operation of one of the heading mechanisms, and contiguous parts. Figs. 38 and 39 are detail views showing the method of cutting the wrapper. Fig. 40 is a sectional view of the reservoir for the paste.

The illustrated embodiment of this invention comprises a frame, actuating means including a single driving element, and right- and left-hand independently-operating hoppers, filler-conveyers, rolling mechanisms, wrapper-controllers and heading mechanisms. Said right- and left-hand devices are preferably employed, since in making cigars the wrappers formed from the opposite halves of tobacco leaves must be rolled in reverse directions, but it is obvious that 90 one of the hoppers, and the corresponding filler-conveyer, rolling mechanism, wrapper-controller, and heading mechanism may be dispensed with. It is also obvious that the hoppers may be omitted and the fillers delivered by hand to the rolling mechanisms.

The frame 1, Fig. 1, may be of any desirable form, size and construction, and as here shown, comprises a base 2, an upright hollow body 3, and a shelf 4 supported by 105 the body 3.

In the preferable construction of this machine, the actuating means comprises a single driving element which includes three horizontal shafts 5, 6 and 7, Figs. 2 and 3, sup- 110

ported by the frame 1. The shaft 5, Fig. 3, extends forwardly from the rear of the machine, terminates at its forward end within the hollow body 3 of the frame 1, and is 5 suitably supported by the body 3 and the rear part 8 of the shelf 4. Said shaft 5 is provided at its inner, or forward, end with a worm 9, Fig. 2, and at its outer, or rear, end with a pulley-wheel 10, Fig. 3, which 10 may be driven by any desirable means, not illustrated. The shaft 6 is arranged at substantially a right angle to the shaft 5, and is journaled at its central portion in a bearing 11, Figs. 3 and 36, in a casing 12 on the 15 rear part 8 of the shelf 4, and at its ends in bearings 13, Fig. 3, on said rear part 8. The portion of the shaft 6 within the casing 12, Fig. 36, is provided with a disk 14 which frictionally engages a worm-gear 15 loosely 20 mounted on said shaft 6 and coaxing with a worm 16 on the shaft 5. Said disk 14, worm-gear 15 and worm 16 constitute means for frictionally connecting the shafts 5 and 6. The ends of the shaft 6 are provided with 25 any suitable means, as ratchet-wheels 17, from which power is transmitted to the heading mechanisms. Owing to the frictional connection of the shafts 5 and 6, either, or both, of the heading mechanisms 30 may be held, or prevented, from operation without stopping the rotation of the shaft 5, or causing breakage of the parts. The shaft 7, Fig. 2, is arranged substantially parallel to the shaft 6, is supported in bearings 35 18 in the side walls of the body 3 of the frame 1, and is provided at its central portion with a worm-gear 19 meshing with the worm 9 on the shaft 5, and at its ends with any desirable means, as ratchet-wheels 20, Fig. 13, from which power is transmitted to the hoppers, filler-conveyers, rolling-mechanisms, and wrapper-controllers. Although 40 the described single driving element including the shafts 5, 6 and 7 is particularly applicable for use with the remaining parts of our machine, it is apparent that any other suitable driving means may be substituted therefor.

Each hopper, Figs. 2 and 4, preferably 50 comprises a stationary base, a movable wall, a movable member, and a stationary agitator. The base 21 is substantially circular, is fixed to the upper portion of the body 3 of the frame 1, and is formed with a discharge- 55 passage 22 opening through the top and the periphery, or vertical edge, of said base. Arranged within the passage 22 is a vertically-adjustable piece or gage 23, Fig. 2, which is held in position by a set-screw 24, 60 and is provided with a face 25 inclining outwardly and downwardly from the interior of the hopper toward the lower portion of the movable wall, presently described, and toward the exit end of the passage 22. The 65 movable wall 26 is cylindrical, and is revolu-

ble about an axis substantially coincident with that of the base 21, and the lower portion of the wall 26 encircles or skirts, and closely fits, the periphery or vertical edge, of the base 21 for closing the outlet or exit 70 end of the discharge-passage 22, and is provided with an opening 27 for registering with said outlet upon each revolution of the wall 26, to permit the discharge of the filler from such passage 22 through the opening 27. 75

In the preferable construction of the hopper, the movable member 28 is journaled in an upright bearing 29 concentric with, and fixed at its upper end to the base 21 and 80 mounted on and rising from the top plate of the body 3 of the frame 1, and said member 28 is revolvable about an axis substantially coincident with that of the movable 85 wall 26. The lower end of the movable member 28 extends within the body 3 of the frame 1 and beneath the top plate of said body, Fig. 2, and is provided at its lower extremity beneath said top plate with a gear 30, and the upper end of said member 28 90 extends above the base 21 and is provided at its upper extremity with a plurality of radial arms 31 fixed at their inner ends to the member 28 and at their outer extremities to the inner face of the wall 26 for causing 95 said wall to revolve with the member 28. Said member 28 and wall 26 make a complete revolution upon each operation of the machine, and during such revolution the arms 31 move successively above the inlet of 100 the discharge passage 22 in a plane intersecting a line coincident with the axis of said inlet and thus force the filler into position to feed into the discharge-passage 22. These arms 31 are provided with laterally- 105 extending parts 32, Fig. 4, for facilitating forcing of the filler into position to feed into the discharge-passage 22, the advance portion of each of these parts 32 having cutting means, as a knife 33, which coacts with 110 a knife 34, forming an upper edge of the discharge-passage 22, to cut off portions of the filler projecting above the upper end of the discharge-passage. The advance portions of the parts 32 extend downwardly toward the top face of the base 21 and thus, as the arms 31 rotate, they tend to raise somewhat, and loosen, the filler directly above the base. Upon reaching the limit of each rotation, the part 32 of one of the arms 115 31 registers with the inlet of the discharge-passage 22, and thus serves to intermittently close such inlet. Simultaneously with the closing of said inlet, the opening 27 in the wall 26 registers with the outlet or 120 exit end of the discharge-passage 22, thus permitting the filler measured within said passage, to be discharged therefrom through the opening 27. The stationary agitator 35 usually consists of a bar which is supported 125 130

by an upright standard 36 on the frame 1 at the outside of the movable wall 26, and projects from the top of the wall 26 downwardly and centrally within the same and 5 then radially relatively thereto, or in other words, laterally toward the inner face of said wall at an angle to a line coincident with the axis of the inlet of the passage 22, the radial portion of said bar being illustrated as provided with arc-shaped arms 37 substantially concentric with said inner face and arranged above the path of the arms 31 for engaging the filler as it is carried about by the arms 31 and the wall 26, and thus 10 stirring and loosening said filler. The described hopper is particularly simple in construction and efficient in operation, but our invention is not limited thereto, as any other desirable hopper may be substituted therefor.

As here illustrated, the movable member 28 of the hopper is rotated by mechanism connecting the gear 30 and the ratchet-wheel 20, and including an upright shaft 38, Fig. 25, a sleeve 39, and power-transmitting mechanism between the sleeve 39 and the ratchet-wheel 20. The shaft 38 is arranged within the body 3 substantially parallel to the axis of said member 28, is journaled in bearings 30 40, 41 in the body 3, and is provided on its upper end with a gear 42 meshing with the gear 30 on the member 28, and on its lower end with a bevel-gear 43 meshing with a bevel-gear 44 fixed on the contiguous, or 35 inner, end of the sleeve 39, the latter being loosely mounted on the shaft 7, and projecting through the bearing 18 in the side wall of the body 3. Said power-transmitting mechanism between the sleeve 39 and 40 the ratchet-wheel 20 includes a revoluble member 45, Figs. 13 and 14, fixed to the outer end of the sleeve 39, and provided with an independently-movable part, as a pawl 46, for coacting with the ratchet-wheel 45 20. Normally, the pawl 46 is held out of operative engagement with the ratchet-wheel 20 by a suitable means serving to control the movement of said pawl into and out of engagement with such ratchet-wheel. 50 Said means generally includes two sections 47, 48, Figs. 22 and 23, and means for operating the same. The section 47 is slideable rectilinearly, substantially parallel to the shaft 7, in a guide 49 formed in a bracket 55 supported by the frame 1, and is provided with a spring arm 50 for coacting with the pawl 46 to hold the same in inoperative position against the action of a spring 51, Figs. 13 and 14, which tends to force the 60 pawl 46 into engagement with the ratchet-wheel 20; and the other section 48 is supported by the section 47, is pivotally connected thereto at 52, and is normally arranged substantially parallel to the line of 65 movement of said section 47.

Usually, the means for operating the sections 47, 48 includes a plurality of members 53, 54, Figs. 22 and 23, arranged one above the other, and actuated manually and independently of each other. Said members 53, 70 54 are pivoted intermediate of their ends to the frame 1, at 55, corresponding arms 56, 57 thereof being formed, respectively, with diverging faces 58, 59 and shoulders 60, 61 for coacting with the section 48. Upon 75 operating the member 53, the face 58 thereof will engage a side edge of the section 48 and rock the same on the pivot 52 relatively to the section 47, thus carrying an end edge 62 on said section 48 into the path of the shoulder 61 of the member 54. Upon subsequently rocking the member 54, the shoulder 61 thereof will engage the edge 62 of the section 48 and force both sections 48, 47 rectilinearly in one direction from their 80 operative position, whereupon the spring arm 50 will be disengaged from the pawl 46, and said pawl will be forced into engagement with the ratchet-wheel 20 by the spring 51. If the member 54 is operated first, the face 90 59 thereof will engage the opposite side edge of the section 48 and rock said section on the pivot 52, so that the end edge 62 of the section 48 will be arranged in the path of the shoulder 60 on the member 53, and consequently, when the member 53 is operated, its shoulder 60 will coact with the edge 62 and force both the sections 48, 47 rectilinearly. When the members 53, 54 are released, a 95 spring 63, Fig. 22, returns them to their normal position, and a spring 64 and spring plate 65, Figs. 22 and 23, return the sections 47, 48 to their normal position.

The spring 64, Fig. 23, is interposed between shoulders 66, 67, provided, respectively, on the section 47, and the bracket formed with the guide 49, and forces the sections 47, 48 rectilinearly to the position from which they are moved by either of the members 53, 54 when coacting with the section 48. The spring plate 65 is fixed at one end by screws 68 to said bracket, and is formed at its opposite, or free, end with a substantially T-shaped cutout 69 for receiving a shoulder 70 provided on the contiguous end of the section 48, and having a beveled face 71 for raising the free end of the plate 65 which yields to allow the movement of the section 48 rectilinearly with the section 47 by the members 53, 54. Said cutout 115 70 is provided with cam-faces 72 which diverge from the central portion of such cutout, and during the movement of the sections 47, 48, by the spring 64, these faces 72 coact with the shoulder 70 to rock the section 48 120 on the pivot 52 to its initial position relatively to the section 47, as indicated by full lines in Fig. 22. These two members or levers 53, 54 are particularly efficient when 125 two operators are working at one side of the 130

machine, since they serve to prevent the premature engagement of the pawl 46 with the ratchet-wheel 20 by one operator before the other is ready for such operation. The described means for controlling the transmission of power from the shaft 7 to the mechanisms driven thereby is particularly applicable for use with the remaining parts of our machine, but any other suitable means 10 may be substituted if desired.

As preferably constructed, each filler-conveyer, Figs. 6 and 7, comprises a movable support 73, a chute 74 for the filler, and a plunger 75 movable in the chute. The support 15 73 is fixed to an oscillating spindle 76 which is journaled in a bearing 77 in the side wall of the body 3 of the frame 1, and projects laterally from such body. Said chute 74 consists of a frame which is open at 20 its upper and lower ends is movable in a guide 78, Fig. 6, formed in the support 73 and is provided at its lower open end with a guide passage of substantially rectangular cross-section in which the plunger 75 is 25 movable, said plunger normally filling the guide passage and preventing the feed of the filler thereto until the chute descends relatively to the plunger 75 as presently described, and the chute and the plunger 30 co-acting to carry the filler during the movement of said parts with the support 73, from their initial position, about the axis of the spindle 76. The plunger 75 forces the filler through the guide passage of the chute 74 to 35 the rolling mechanism, and includes a plurality of sections 79, 80, and springs 81 interposed between said sections 79, 80 one section 79 operating to engage the filler and being driven by the other section through 40 the springs 81. These springs 81 are mounted on rods 82 fixed to the section 80 and 45 slidably in guides 83 in the section 79. Any desirable means, as a rod 84, is fixed to the section 79, and projects through an opening 50 in the section 80, the outer end of said rod being bent laterally to form a shoulder 86 for coacting with the contiguous face of the section 80 to limit the movement of either of the sections 79, 80 from the other. Said 55 rod 84 constitutes rigid means independent of the springs 81 and coacting with the sections of the plunger 75 for returning the section 79 with the section 80. Pivottally carried upon the section 80 of the plunger 75 is 60 a suitable spring-pressed catch 87 which co-acts with a shoulder 88 on the chute 74 for connecting the plunger 75 and the chute 74 together and causing the chute to be retracted from the rolling mechanism by the movement of the plunger from said rolling mechanism.

The filler-conveyer is actuated by means driven by the shaft 7 and including a cam 89, Figs. 2 and 11, revoluble with the shaft 38, a lever 90, Figs. 2 and 10, pivoted inter-

mediate of its ends at 91 to the body 3 of the frame 1, and having one end coacting with the cam 89, and its other end provided with teeth 92, Fig. 10, a rocking arm 93, Figs. 2, 5 and 9, loosely mounted on the spindle 76 70 at the inner side of the support 73, and having teeth 94 coacting with the teeth 92 on the lever 90, and having its free end connected to the driving section 80 of the plunger 75, by a link 95, and a friction-device, 75 Figs. 5 and 9, for effecting the movement of the support 73. Said friction-device is preferably composed of a member, as a spring arm 96 secured to the rocking arm 93, and a member 97 carried by the support 73 80 and frictionally and detachably engaging the arm 96.

Preferably, the filler falls from the discharge-passage 22 of the hopper through the opening 27 into the chute 74 just before 85 the movable wall 26 reaches the end of a revolution, and immediately after the movable wall 26 commences a second revolution, the filler-conveyer starts its operation which is as follows:—The support 73, chute 90 74, plunger 75, and spindle 76 rock simultaneously about the axis of said spindle relatively to the rolling mechanism until the support 73 is prevented from further movement by engagement with the rolling mechanism. When the support 73 reaches the limit of such rocking movement, the catch 87 coacts with an abutment 98 which forces said catch from engagement with the shoulder 88 on the chute 74, whereupon the chute 100 74 with its charge of filler falls by gravity rectilinearly downwardly in the guide 78 and relatively to the rolling mechanism, the support 73, and the plunger 75, until said chute engages the rolling mechanism. The 105 descent of the chute 74 by gravity causes it to move independently of the support 73 and the plunger 75, from the relative position of these parts shown in Fig. 6 to the position relatively to the support 73, indicated in 110 Fig. 7, but although at the end of said descent, the chute 74 and the support 73 are in their relative position shown in Fig. 7, the plunger has not descended from its position relatively to the support 73, as indicated 115 by full lines in Fig. 6. After the chute has moved relatively to the plunger 75 a limited distance, the filler feeds by gravity beneath, or into the path of, said plunger. Upon the stoppage of the movement of the support 73, the arm 93 moves the spring arm 96 out of engagement with the friction-member 97, and also moves the plunger 75 rectilinearly downwardly relatively to the support 73 and the chute 74, thus forcing the 120 filler from the chute to the rolling mechanism, the movement of the plunger 75 continuing until the section 80 thereof has been forced downwardly against the action of the springs 81 a short distance toward the sec- 125 130

tion 79 of said plunger, as shown in Fig. 7. When the section 80 of the plunger 75 reaches the limit of its downward movement, the catch 87 is automatically forced by its spring into operative position in engagement with the shoulder 88 on the chute 74, and consequently, as the arm 93 rocks in the reverse direction, the section 80 of the plunger 75, and the chute 74, are drawn upwardly, but the compressed springs 81 cause the section 79 of said plunger to remain in contact with the filler a predetermined time during the upward movement of said parts 80 and 74. When the shoulder 88 on the rod 84 is engaged by the upwardly moving section 80 of the plunger, both sections 79, 80 and the chute 74 return rectilinearly together relatively to the support 73 until the friction-members 96, 97 are again engaged with each other, whereupon all the movable parts of the filler-conveyer rock about the axis of the spindle 76 to their normal or initial position. Suitable means, as an arm 980, Fig. 3, fixed to the frame 1, supports the filler-conveyer when in its normal or initial position. By maintaining the section 79 of the plunger 75 in engagement with the filler until after the chute 74 has been raised a limited distance above the rolling mechanism, we reduce to a minimum the liability of the filler being lifted from its position on the rolling mechanism upon the return of the filler-conveyer.

The rolling mechanisms, Figs. 12 to 20, inclusive, are arranged on opposite sides of the body 3 of the frame 1, and each preferably comprises a movable member 99, Figs. 13 and 14, a flexible member 100, and rollers 101, 102. The movable member 99 is here illustrated as loosely mounted on a spindle 103 which is fixed to the side wall of the body 3, and projects laterally therefrom, contiguous to, and substantially parallel to, the shaft 7 of the driving means. This member 99 is oscillated to and fro on the spindle 103 by any suitable means, here shown as comprising a cam-groove 104 in the revoluble member 45 of the power-transmitting mechanism between the sleeve 39 and the ratchet-wheel 20 on the shaft 7, and a laterally-projecting pin 105 provided on said member 99 and coacting with the cam-groove 104. It will be apparent that the members 53, 54, previously described, by controlling the transmission of power from the ratchet-wheel 20 to the sleeve 39 provided with the member 45, indirectly control the action of the movable member 99 to which motion is transmitted from the sleeve 39. The upper, or free, end of the member 99 is formed with an arc-shaped table 106 concentric with the axis of said member 99. The flexible member 100, which may be of any desirable form, size, and construction, is here shown as comprising an apron ar-

ranged upon the table 106 and formed of two sections 107, 108, one 107 being composed of a layer of canvas having its extremities fixed, respectively, to one end of the table 106, and to an arm 109 on the member 99, and the other 108 being composed of a layer of rubber secured to the upper, or outer, face of the intermediate portion of the section 107.

The rollers 101, 102, Fig. 13, are normally arranged contiguous to each other beneath a part of the apron 100, and are carried by the free ends of supports 110, 111, pivoted on a common axis and movable independently of each other, one 110 being loosely mounted on a rocking pivot 112, Figs. 12 and 13, journaled in bearings 113 on the front part 114 of the shelf 4, and the other 111 being fixed on said pivot 112 and movable therewith upon each operation of the member 99. When the parts of the machine are in their normal position, Fig. 13, the roller 101 is spaced apart in a horizontal plane from the contiguous end of the table 106, thus forming an opening into which the apron 100 is forced by the filler-conveyer for forming a loop 115 to receive the wrapper, binder, and filler of the cigar. Said support 110 is adjustable, by a set-screw 116, for carrying the roller 101 and the apron 100 relatively to the member 99 to change the size of the loop 115, and is held in its predetermined position by a spring 117. Upon each operation of the machine and after the apron 100 and the roller 101 have coöperated to close the open side of the loop 115 about the contained cigar material the support 111 is rocked with its pivot 112, carrying the roller 102 away from the member 99, Fig. 18, said movement of the roller 102 serving to take up a portion of the length of the apron out of the closed loop 115 for tightening said loop about the parts of the cigar. The support 111 is rocked by suitable power-transmitting means connected to the sleeve 39 and comprising a reciprocating arm 118, Figs. 13 and 20, pivoted at one extremity to the free end of a crank-arm 119 fixed on the pivot 112, and having its other extremity bifurcated and provided with a roller 120, this bifurcated end being astride the sleeve 39, and the roller 120 coacting with a cam 121 fixed to the sleeve 39.

The binder 122 and the wrapper 123, Fig. 15, are placed in position while the machine is at rest, and after the operation of the members 53, 54, the hopper and the filler-conveyer are actuated to supply the filler 124, Figs. 15 and 16, to the loop 115, and to force said filler and the underlying portions of the binder and the wrapper into such loop. During the initial operation of the rolling mechanism, the member 99 moves forward and carries the advance end of the table 106, and a portion of the apron 100,

toward the roller 101, thereby closing the open side of the loop 115, and immediately after such initial operation, the support 111 is rocked on its pivot by the arm 118 and the cam 121. Further forward movement of the member 99 carries the apron therewith, thus continuously changing the portion of the apron forming the loop 115 and rolling the binder and the wrapper simultaneously about the filler. When the member 99 reaches the limit of its forward movement, the rear end of the table 106 passes beyond the roller 101, and effects the removal of the loop 115 from the apron, and the engagement of the cigar with suitable holding means, as arms 125, Fig. 14, fixed to said rear end of the table 106.

The wrapper-controller, Figs. 12 to 21, inclusive, operates to control the rolling of the wrapper about the filler and the binder, and generally includes a support 126, Fig. 12, for the wrapper, and two sections 127, 128. Said support 126 is composed of sheet-metal, and is fixed to an arm 129 secured to the body 3 of the frame 1. The section 127 is pivoted at 130 to the section 128, and said section 128 is pivoted at 131 to the free, or upper, end of an actuating arm 132, Fig. 20, having its opposite end pivoted on a hub 133 provided on the member 99 concentric with the spindle 103, the pivot 131 being arranged at an angle to the spindle 103. This section 128 is connected by a link 134, Fig. 13, to the free, or upper, end of a second actuating arm 135 pivoted on the hub 133. Tension-members, as rollers 136, 137, are carried, respectively, by the free end of the section 127 and the opposing part of the section 128, and operate to engage opposite sides of the wrapper for tensioning the same when being rolled about the filler and the binder and for holding the wrapper in the desired position to present the same at the proper angle. The free end of the section 127 is normally separated from the section 128, and is held in such position by a spring 138. Mounted on the hub 133 at opposite sides of the arms 132, 135, and between the member 99 and an adjustable collar 139, Fig. 19, on said hub, are friction-devices, as washers 140, for causing the actuating arms 132, 135 to be operated by the member 99, and permitting said member to move relatively to such arms 132, 135. Secured to the section 128 is a pivoted locking member 141, Figs. 12 and 21, held in its operative position by a spring 142, Fig. 21, and provided on its free end with a shoulder 143 for co-acting with the section 127 to hold the same in operative position. The upper face of the shoulder 143 is tapered or beveled and is arranged in the path of the contiguous portion of the section 127. Consequently, as the section 127 is forced into its operative

position against the action of the spring 138, 65 said section engages the tapered upper face of the shoulder 143 and forces the same outwardly against the action of the spring 142, and when the section 127 reaches its operative position, the shoulder 143 is automatically forced inwardly by the spring 142 into position to prevent the return movement of the section 127 by the spring 138.

In the use of the machine, the wrapper is placed upon the table 126 and the roller 137, 75 and the binder upon the apron 100, portions of said wrapper and binder being in position to be forced into the loop 115 by the filler-conveyer. During the operation of the filler-conveyer to supply the filler and 80 form the loop 115, as previously described, the rocking support 73 of said filler-conveyer engages the section 127 of the wrapper-controller and forces the same downwardly against the action of the spring 138 85 until the roller 136 engages the wrapper, whereupon the spring 142 automatically forces the locking member 141 into position to restrain the return movement of the section 127 by the spring 138. 90

During the initial forward rocking movement of the member 99, in the operation of the rolling mechanism, the friction-washers 140 cause the actuating arms 132, 135 to rock about the axis of the spindle 103 with the member 99, until the arm 132 is prevented from further movement by a stop 144, Fig. 20, adjustably mounted on a fixed rod 145 projecting from the part 114 of the shelf 4. The movement of the arm 132 forces the sections 127, 128 of the wrapper-controller forwardly with the member 99 and the apron 100, and the movement of the arm 135 rocks said sections on the pivot 131. After the arm 132 has been limited in its forward 100 movement with the member 99, the arm 135 moves with said member 99 relatively to the arm 132 until said arm 135 is prevented from further forward movement by engagement with a stop 146 adjustably supported by the arm 132. The latter movement of the arm 135 additionally swings the sections 127, 128 on the pivot 131 relatively to the rolling mechanism. As the member 99 is approaching the limit of its forward movement, an arm 147, Fig. 12, carried thereby coacts with the locking member 141 and forces the same from operative position against the action of the spring 142, whereupon the spring 138 returns the section 127 115 to its normal position. During the backward movement of the member 99, the arms 132, 135, owing to the action of the friction-washers 140, rock backwardly simultaneously with said member 99, until the arm 132 is limited in its return movement by a stop 148 adjustably mounted on the rod 145, after which the arm 135 returns with the 120 125

member 99 until prevented from further movement by a stop 149 adjustably supported by the arm 132.

Secured to the free end of the section 127 of the wrapper-controller, and in advance of the roller 136, is a guide-member 150, Fig. 12, which coacts with the wrapper when passing between the rollers 136, 137, and the loop 115 of the apron 100, for guiding the wrapper into said loop.

At the commencement of the operation of the machine, the binder rests upon a member 151, Figs. 12 and 17, which is pivotally supported upon the side part 152 of the shelf 4, and is provided with a spring-arm 153 frictionally connected to the edge of the table 106 to be rocked thereby. As the member 99 moves forwardly, the member 151 is rocked on its pivot and moves the outer, or rear, portion of the binder across the open side of the loop 115 toward the portion of the apron embracing the roller 101, and as the member 99 moves rearwardly, it returns the member 151 to its normal position. The purpose of moving the binder, as described, is to prevent the filler from being forced through the open side of the loop 115. The heading mechanisms are supported by the shelf 4 at opposite sides of the body 3, and each comprises a holder for the cigar, a thimble for finishing the head end of the cigar, and knives. Said holder for the cigar, Figs. 24 and 32, is composed of a section 154 fixed to a support 155, and a section 156 fixed to the free end of a movable arm 157 having its other end pivoted at 158 to the support 155, these sections 154, 156 being formed with concave faces 159, 160 for engaging opposite surfaces of the cigar. Normally, the section 156 is separated from the section 154, and is held in such position by a cam 161, Fig. 32, which is fixed to a revolute actuating shaft 162 and coacts with a shoulder 163 on the arm 157. Before the heading mechanism is operated, the cigar is removed by hand from the arms 125 of the rolling mechanism and placed upon the section 154 of the cigar-holder, and immediately upon the commencement of the revolution of the shaft 162, the cam 161 is rotated out of engagement with the shoulder 163, whereupon a spring 164 rocks the free end of the arm 157 downwardly carrying the section 156 into position to coöperate with the section 154 for holding the cigar stationary. When the shaft 162 is assuming the limit of its rotation, the cam 161 again engages the shoulder 163, and rocks the free end of the arm 157 upwardly against the action of the spring 164, thus moving the section 156 from the section 154 to release the cigar within the holder.

A removable part 165, Figs. 31 and 32, projects through an opening in the section

154 of the cigar-holder, and is provided with any desirable means for marking the cigar. As shown in Fig. 32, a suitable device, as an alcohol-lamp 166, may be utilized for heating the removable part 165 to facilitate marking of the cigar by said part 165. The actuating shaft 162 is journaled in bearings 167, 168, Fig. 35, is rotated by the shaft 6 of the driving element, previously described, and is connected to the shaft 6 by a sleeve 169, Figs. 3 and 24, and means coöperating therewith. Said sleeve 169 is loosely mounted on the end of the shaft 6, is journaled in the bearing 13, and is provided at one end with a bevel-gear 170 meshing with a bevel-gear 171 fixed on the shaft 162, and at its other end with a radial arm 172, Fig. 37, on which is pivotally supported a pawl 173 for coacting with the contiguous ratchet-wheel 17 on the shaft 6. When the pawl 173 is engaged with the ratchet-wheel 17, these parts 17, 173, and the arm 172, sleeve 169 and gears 170, 171 connect the shafts 6 and 162.

Preferably, independently-operating means is provided to control the connection of the heading mechanisms to the shaft 6, and as here shown, each of said means comprises a manually-operated member 174, Figs. 24 and 37, pivoted intermediate of its ends in a bearing 175, Fig. 27, one arm 176 of said member serving as a hand-piece, and the other arm 177 thereof operating to engage the pawl 173 and hold the same against the action of a spring 178, out of position to coact with the ratchet-wheel 17. When it is desired to operate the heading mechanism, the member 174 is rocked on its pivot moving the free end of its arm 177 laterally out of engagement with the pawl 173, whereupon the spring 178 engages said pawl with the ratchet-wheel 17, and motion is transmitted to the heading mechanism. Immediately after the commencement of the operation of the heading mechanism, the member 174 is released and is then returned to its normal position by a spring 179. Consequently, when the shaft 162 reaches the limit of each rotation, the pawl 173 engages the free end of the arm 177 and is forced out of engagement with the ratchet-wheel 17, thus causing the operation of the heading mechanism to cease.

The thimble, Figs. 30 and 31, includes a plurality of movable sections 180, 181 and 182, is provided with a recess 183 for receiving the head end of the cigar, is arranged at one end of the holder for the cigar, and is revolute in a bearing 184 having its axis substantially coincident with that of the cigar when clamped by such holder. Said bearing 184 is formed in opposing faces of a fixed support 185 and a movable carrier 186. Each of the sections 180, 181 of the thimble is provided with a

semicircular series of teeth, Fig. 27, and when the thimble is closed, these series of teeth form a pinion 187, Fig. 29, for meshing with a revoluble power-transmitting element, or gear, 188. Said sections 180, 181 are also provided with peripheral cutouts, Figs. 30 and 31, angular in cross-section, forming a groove 189 for receiving an annular shoulder 190 of substantially the same 10 cross-section as such groove, and provided within the bearing 184, said groove 189 and shoulder 190 coacting to hold the thimble within the bearing 184. The section 180 comprises substantially one-half of the 15 thimble, and is provided with one-half of the recess 183, and with a knife 191, Fig. 31, having an angularly-extending edge, one portion of which is arranged along one of the sides of the inner end of the recess 183, 20 and the other portion of which extends crosswise of the point of said recess. The sections 181, 182 comprise the other half of the thimble, and are each provided with a one-quarter of the recess 183. When the 25 thimble is closed, opposing surfaces of the sections 180, 181 at one side of the recess 183 are in contact, and the like surfaces of the sections 180, 182 at the opposite side of such recess are slightly spaced apart to 30 receive the free end of the wrapper.

The section 181 of the thimble is normally separated from the section 180 and the gear 188, as seen in Fig. 27, and is automatically movable by the carrier 186 in a 35 plurality of directions into and out of operative position to partially close, and open, the thimble. This carrier 186 is loosely mounted on a shiftable pivot 192, Figs. 26 and 32, is engaged, and movable upwardly 40 on its pivot, by a cam 193 fixed to the shaft 162, and moves downwardly on said pivot by gravity until opposing surfaces of the sections 180, 181 are in contact. The pivot 192 is secured to the free end of a support 45 194 which is pivoted at 195 to suitable bearings on the shelf 4 of the frame 1, and is rocked in one direction by a spring 196, and in the opposite direction by a cam 197, Fig. 26, fixed to the shaft 162, and coacting with 50 a roller 198 on said pivot 192.

The section 182 of the thimble is supported by the section 181, is movable therewith relatively to the section 180, and is movable automatically endwise of the axis 55 of the cigar and the thimble, relatively to said section 181 into and out of operative position to completely close, and partially open, the thimble. The end of the section 182 nearest the point of the portion of the recess 183 within such section is provided with a lateral extension 199, Figs. 28 and 29, fixed to corresponding ends of two parallel parts or rods 200 movable in guides or openings extending through the section 181 parallel to the axis of the thimble. Secured to

the opposite ends of the rods 200 and arranged concentric with the axis of the thimble, is a ring 201, Figs. 25, 26 and 30, having a radial passage 202 for receiving the contiguous portion of the cigar and permitting the ring 201 to move with the sections 181, 182 of the thimble into and out of operative position relatively to the cigar. Said ring 201 is provided with a peripheral groove 203 for receiving an actuating member 204, Figs. 25 and 26, and permitting revoluble movement of the section 182 and the ring 201 relatively to such member 204. This member 204 is fixed to one end of a reciprocating sleeve 205, Figs. 25 and 26, 80 mounted on a guide, or rod, 206, and provided with a pin 207 arranged in a slot 208 in one end of an actuating arm 209 pivoted intermediate of its ends at 210, Fig. 26, to the bearing 168 of the shaft 162. Longitudinally-adjustable engaging parts, as screws 211, 212, Figs. 25 and 26, are provided on the arm 209 at opposite sides of the shaft 162 and coact, respectively, with cams 213, 214 revoluble with the shaft 162. Said engaging parts 211, 212 and cams 213, 214, serve to rock the arm 209 in reverse directions, and thereby move endwise the sleeve 205, the actuating member 204, the ring 201, and the section 182 of the thimble. 95 The member 204 is formed with an upwardly-extending arm 215 which is substantially concentric with the pivot of the carrier 186, and coacts with the walls of the groove 203 to prevent endwise movement of 100 the section 182 of the thimble relatively to the section 181. Any desirable means is provided for preventing revolution of the section 182 when in inoperative position, the same including a shoulder 216, Figs. 25 and 26, on the carrier 186, and a notch 217 which is formed in the ring 201 and receives the shoulder 216 when the section 182 is moved endwise to said inoperative position.

When the cigar is placed in proper position upon the section 154 of the holder, its head end is within the one-half of the recess 183 in the section 180 of the thimble, and the free end of the wrapper extends from the sides and point of the head of the cigar, a considerably greater portion of the wrapper extending from one side of the point than from the other side thereof, as seen in Fig. 39. During the initial part of a rotation of the shaft 162, the cams 161 and 195 are moved out of engagement with the shoulder 163 and the carrier 186, whereupon the spring 164 moves the free end of the arm 157 downwardly for engaging the holder-section 156 with the cigar, and gravity moves the free end of the carrier 186 downwardly at an angle to the axis of the thimble for forcing the thimble-sections 181, 182 toward the thimble-section 180 into their position assumed in Fig. 28. The sec- 130

tions 181, 182 are then at one side of the position occupied thereby when the thimble is entirely closed, the opposing surfaces of the sections 180, 181 are in contact, and the like surfaces of the sections 180, 182 are spaced apart sufficiently to prevent binding of the free end of the wrapper which is interposed between said surfaces of the sections 180, 182.

10 After the thimble-sections 181, 182 have been depressed to the position illustrated in Fig. 28, the cam 197 moves the carrier 186 endwise and forces said sections laterally or radially of the thimble, thus engaging the series of teeth provided on the section 181 with the gear 188, as shown in Fig. 29. By moving the sections 181, 182, as described, we reduce to a minimum any liability of the wrapper being caught between opposing surfaces of the sections 180, 181 and 182 at one side of the recess 183. After the cam 197 has moved the carrier 186 endwise, the cam 214 moves the arm 209 on its pivot and forces the thimble-section 182 endwise 20 relatively to the sections 180, 181, and entirely closes the thimble. The gear 188 then rotates the thimble, and during such rotation the head end of the cigar is finished. Before the shaft 162 makes a complete revolution, the gear 188 ceases to revolve the thimble, after which the cam 213 actuates the arm 209 to move the thimble-section 182 endwise in the reverse direction until the notch 217 in the ring 201 has received the shoulder 216, whereupon the cam 197 permits the spring 196 to move the carrier 186 endwise, and the cams 163 and 193, respectively, raise the free end of the holder-section 156, and the similar end of the carrier 186 supporting the thimble-sections 181, 182. The finished cigar may then be removed from the holder-section 154 and the thimble-section 180.

While the sections 181, 182 of the thimble are moving into and out of operative position, it is necessary to have the gear 188 remain stationary relatively to the shaft 162. Consequently, the gear 188 is loosely mounted on the shaft 162 and is connected to such shaft during parts of each revolution thereof. Generally the means for connecting the gear 188 to the shaft 162 comprises a plurality of shoulders 218, Fig. 27, fixed on the gear 188 in a series concentric with the axis 50 of said gear, and also a movable shoulder 219, Fig. 35, provided on a slide which is arranged in a radial opening 220 in a disk 221 fixed on the shaft 162, and is forced outwardly from the axis of the disk 221 by a spring 223 mounted in the opening 220. Said slide is also provided with an extension 224 coacting with a suitable stationary cam 225, Fig. 27, to move the shoulder 219 inwardly toward the axis of the disk 221 into inoperative 55 position, and to hold said shoulder in

such position, said cam being of sufficient length to prevent the shoulder 219 from assuming its outward, or operative, position during the last portion of each revolution of the shaft 162 and the first portion of the subsequent revolution. The shaft 162 revolves independently of the gear 188 when the shoulder 219 is held from engaging the shoulders 218, and said gear revolves with the shaft 162 when the shoulder 219 engages one of the shoulders 218. 70

At the commencement of the operation of the heading mechanism, the shaft 162 and the gear 188 are in the positions assumed in Fig. 27, the shoulder 219 being held by the cam 225 out of position to engage the shoulders 218, and the gear 188 being disconnected from the shaft 162. During the first part of the revolution of the shaft 162, the cam 225 continues to hold the shoulder 219 in its inoperative position, but upon the further rotation of the shaft 162, the shoulder 219 passes beyond an end of the cam 225 in advance thereof, whereupon the spring 223 forces said shoulder outwardly into operative position. As the shaft 162 continues its revolution, the shoulder 219 engages the first shoulder 218 in advance of the cam 225, after which the gear 188 revolves with said shaft until the shoulder 219 is engaged with the other end of the cam 225, whereupon the cam 225 forces the shoulder 219 inwardly against the action of the spring 223 and disconnects the gear 188 from the shaft 162. Said shaft 162 then continues its revolution independently of the gear 188. 95

Means is preferably provided for preventing revolution of the gear 188 when disconnected from the shaft 162, said means including a locking part 226, Fig. 35, arranged at an angle to the gear 188 and movable endwise into and out of position to coact with suitable stop-means, as openings 227, Fig. 27, in said gear. A spring 228, Fig. 35, moves the locking part 226 into its operative position, and a cam 229 fixed on the shaft 162 effects movement of the locking part 226 in the reverse direction, this cam engaging one end of a pin 230 movable endwise in the bearing 167 for the shaft 162, and having its other end engaged with a rocking arm 231 which is pivoted at one side of the pin 230 to the bearing 167, and is pivoted at the opposite side of said pin to the locking part 226. When the movable shoulder 219 is disconnected by the cam 225 from one of the shoulders 218, the cam 229 permits the spring 228 to force the locking part 226 toward the gear 188 and into one of the openings 227, and when the shoulder 219 is forced into operative position by the spring 223, said cam 229 simultaneously forces the locking part 226 from operative position. 110

The knives of the heading mechanism are 130

preferably secured to the disk 221, one knife 232 being rotated between the opposing end surfaces of the thimble-sections 180, 181, and the thimble-section 182 just before said section 182 is moved endwise into its operative position, and having an angularly-extending cutting edge which coacts with the similarly-arranged edge of the knife 191 to cut the free end of the wrapper along the side, and crosswise of, the head end of the cigar, as seen in Fig. 39, and the other knife 233 being rotated past the outer ends of the sections 180, 181 and 182 after the section 182 assumes its operative position, and being formed with a single cutting edge for trimming the wrapper crosswise of the head end of the cigar.

During the operation of the knife 232 the free end of the wrapper is held from tearing by suitable clamping means comprising a part 234, Fig. 30, and a support 235, Fig. 38, the part 234 consisting of a thin plate, spaced apart from the sections 180 and 181 of the thimble, and fixed to an arm 236 projecting from the outer end of said section 181, and the support 235 consisting of the weighted end of a lever 237 pivoted intermediate of its ends on a fixed pivot 238. This support 235 is movable independently of the thimble into and out of position to coact with the clamping part 234. The other arm 239 of the lever 237 is engaged and operated by a pin 240, Figs. 25 and 27, fixed on the disk 221. When the sections 181, 182 of the thimble are moved into operative position, the clamping part 234 is carried into engagement with the upper side of the wrapper, and immediately afterward the pin 240 coacts with the arm 239 of the lever 237 and moves the support 235 to its position assumed in Fig. 38 in engagement with the lower side of the wrapper, and holds said support in such position until after the knife 232 has moved between the thimble-sections 180, 181, and the thimble-section 182 and the clamping parts 234, 235 to cut the wrapper. The rotation of the disk 221 then carries the pin 240 out of engagement with the arm 239, whereupon the weighted end of the lever 237, terminating in the support 235, moves by gravity to its inoperative position, and the thimble-section 182 is forced to its operative position.

This machine also preferably includes means for removing the wrapper-trimmings from the knife 233, the same comprising a revolute member 241, Figs. 3 and 27, having a plurality of radial yielding arms 242 movable at opposite sides of the path of the knife 233. The member 241 is connected to the driving shaft 5 by any suitable means, as a belt 243, Fig. 3.

In the illustrated construction of this invention, we provide a closed paste-containing reservoir 244, Figs. 3 and 40, supported

by the frame 1. This reservoir includes an inlet-valve 245 through which air under pressure is driven into the reservoir by any suitable means, not illustrated, said air serving to force the paste from the reservoir. A conduit 246 extends from the reservoir 244 for conducting the paste therefrom, and its free end is supported by any desirable means, as a standard 247 and a brace 248, Fig. 27. This conduit is provided with a revolute lateral branch of substantially right-angular form, the free end of one arm 249 of the branch being journaled in the main part of the conduit in alinement with the axis of the thimble, and the free end of the other arm 250 of said branch being connected to the axis of the thimble and communicating with the portion of the recess 183 in said thimble-section. By connecting the lateral branch of the conduit 246 to the thimble eccentric to its axis, the knives 232 and 233 are permitted to revolve to cut the wrapper without interfering with the arm 250 of said branch. The conduit 246 is provided with a valve 251 for controlling the flow of the paste therethrough, said valve having an arm 252 which is engaged by the pin 240 on the disk 221. During each revolution of the shaft 162, the pin 240 operates the arm 252 to open the valve 251 a sufficient length of time to permit the required amount of paste to enter the recess 183 from the lateral branch of the conduit 246.

This machine is preferably provided with knives 253, 254, Figs. 3 and 33, for trimming the tuck end of the cigar, the knife 253 being fixed to a support 255 and provided with a V-shaped cutting edge arranged at one end of the holder for the cigar in alinement with the cigar when clamped by said holder, and the knife 254 being journaled at one end in the support 255, and provided at its other end with a V-shaped edge for coacting with the cutting edge of the knife 253. Said support 255 is generally adjustable in a direction coincident with the axis of the cigar when clamped by the cigar-holder, and is held in position by a bolt 256. The adjustment of the support 255 varies the position of the knives 253, 254 for trimming the tuck ends of cigars of different lengths. A gear 258 is fixed to the revolute knife 254 and meshes with a gear 259 which is carried by the support 255, and meshes with a gear 260 fixed to the shaft 162 and formed of greater width than the gears 258, 259 in order to avoid disconnecting the gears 259, 260 during the adjustment of the support 255. When the cigar is laid upon the section 154 of the cigar-holder, the tuck end of the cigar rests upon the cutting edge of the fixed knife 253, and upon the operation of the heading mechanism, the knife 254 is revolved from its position assumed in Fig. 33

and coöperates with the stationary knife 253 to properly trim said end of the cigar.

After the cigar is headed and trimmed, as described, it may be discharged from the section 154 of the cigar-holder into a suitable receptacle 261, Fig. 3, by any desirable means, as an arm 262, Fig. 32, which is loosely mounted on the pivot 158 of the section 156 of said cigar-holder, is held in its normal position by a spring 263, and is actuated at the appropriate time by a cam 264 provided on the shaft 162, and coacting with a shoulder 265 on the arm 262.

The described filler-conveyers, rolling-mechanisms, wrapper-controllers, and heading mechanisms are particularly simple and efficient and adapted for conjoint use, but we do not restrict this invention to the particular constructions of these parts set forth herein, nor to a machine containing all of said structures.

The heading mechanisms illustrated and described herein form the subject-matter of our pending application Serial No. 790,552.

25 What we claim is:

1. In a cigar making machine, the combination of a hopper comprising a stationary circular base having a discharge passage opening through the top and the peripheral face thereof, and a cylindrical wall having the lower portion thereof skirting the peripheral face of the base and closing the exit end of the discharge passage, said wall being revoluble about the axis of the base and having an opening in the portion thereof skirting the base, for registering with the exit end of such discharge passage, and means for rotating the cylindrical wall, substantially as described.

40 2. In a cigar making machine, the combination of a hopper comprising a stationary circular base having a discharge passage opening through the top and the peripheral face thereof, a cylindrical wall having the lower portion thereof skirting the peripheral face of the base and closing the exit end of the discharge passage, said wall being revoluble about the axis of the base and having an opening in the portion thereof skirting the base for registering with the exit end of such discharge passage, and an adjustable piece in the passage for regulating the size thereof, and means for rotating the cylindrical wall, substantially as described.

45 3. In a cigar making machine, the combination of a hopper comprising a stationary circular base having a discharge passage opening through the top and the peripheral face thereof, a cylindrical wall having the lower portion thereof skirting the peripheral face of the base and closing the exit end of the discharge passage, said wall being revoluble about the axis of the base and having an opening in the portion thereof

of skirting the base for registering with the exit end of such discharge passage, and an adjustable piece in the passage for regulating the size thereof, said piece having a face inclining downwardly and outwardly 70 toward said lower portion of the cylindrical wall and the exit end of said passage, and means for rotating the cylindrical wall, substantially as described.

4. In a cigar making machine, the combination of a hopper comprising a stationary base having a discharge passage, a movable member for forcing material into position to move into the discharge passage, said member being journaled in the base and 75 having a part thereof serving as a closure for the inlet of the discharge passage, and a wall revoluble with said member and closing the exit end of the discharge passage, said wall being provided with an opening 80 for registering with said exit end, and mechanism for rotating said member and wall, substantially as described.

5. In a cigar making machine, the combination of a hopper comprising a base, a 90 discharge passage, a movable member formed with a plurality of arms movable successively above the base and the inlet of the discharge passage in a plane intersecting a line coincident with the axis of said 95 inlet and thereby stirring the material and forcing material into position to move into the discharge passage, one of the arms serving as a closure for the inlet, and one of the arms having a part thereof extending in 100 the direction of its movement, toward the base and thereby tending to move the material from the base and loosen said material, and means for opening and closing the exit end of the discharge passage, and mechanism for moving said member, substantially as described. 105

6. In a cigar making machine, the combination of a hopper comprising a stationary circular base having a discharge passage 110 opening through the top and the peripheral face thereof, a cylindrical wall having the lower portion thereof skirting the peripheral face of the base and closing the exit end of the discharge passage, said wall being revoluble about the axis of the base and 115 having an opening in the portion thereof skirting the base, for registering with the exit end of such discharge passage, and a member fixed to said cylindrical wall and 120 movable above the inlet of the discharge passage in a plane intersecting a line coincident with the axis of said inlet and thereby forcing material into position to move into the discharge passage, and means 125 for rotating the cylindrical wall, substantially as described.

7. In a cigar making machine, the combination of a hopper comprising a stationary circular base having a discharge pas- 130

- sage opening through the top and the peripheral face thereof, a cylindrical wall having the lower portion thereof skirting the peripheral face of the base and closing the exit end of the discharge passage, said wall being revoluble about the axis of the base and having an opening in the portion thereof skirting the base, for registering with the exit end of such discharge passage, and a plurality of arms fixed to the inner face of the cylindrical wall and movable successively above the inlet of the discharge passage in a plane intersecting a line coincident with the axis of said inlet and thereby forcing material into position to move into the discharge passage, one of the arms serving as a closure for said inlet, and means for rotating the cylindrical wall, substantially as described.
8. In a cigar making machine, the combination of a hopper comprising a stationary circular base having a discharge passage opening through the top thereof, a cylindrical wall revoluble about the axis of the base and having means for controlling the exit of material from the discharge passage, and a stationary agitator supported outside of the cylindrical wall and projecting from the top thereof downwardly within said wall, and mechanism for rotating the cylindrical wall, substantially as set forth.
9. In a cigar making machine, the combination of a hopper comprising a stationary circular base having a discharge passage opening through the top and the peripheral face thereof, a cylindrical wall having the lower portion thereof skirting the peripheral face of the base and closing the exit end of the discharge passage, said wall being revoluble about the axis of the base and having an opening in the portion thereof skirting the base for registering with the exit end of such discharge passage, and a stationary agitator supported outside of the cylindrical wall and projecting from the top thereof downwardly within the same and then laterally toward the inner face of said wall at an angle to a line coincident with the axis of the inlet of said passage, the laterally projecting portion of the agitator being provided with arc-shaped arms substantially concentric with said inner face, and mechanism for rotating the cylindrical wall, substantially as set forth.
10. In a cigar making machine, the combination of a hopper comprising a stationary base having a discharge passage, revoluble means for closing and opening the exit end of the passage, a member for forcing the material into position to move into the discharge passage, the member being fixed to said means and revoluble therewith, and an agitator fixed from movement with said means and member and arranged to engage

the material when being moved by said member, substantially as set forth.

11. In a cigar making machine, the combination of a hopper comprising a stationary circular base having a discharge passage opening through the top and the peripheral face thereof, a cylindrical wall movable about the axis of the base and having a portion skirting the peripheral face of the base and closing the exit end of said discharge passage, the portion of the cylindrical wall skirting the base also having an opening for registering with said exit end, and the cylindrical wall having an inwardly extending arm for forcing the material into position to move into the discharge passage, said arm serving as a closure for the inlet of the discharge passage, and a fixed agitator arranged to engage the material when being moved by said arm, and actuating mechanism for the cylindrical wall, substantially as set forth.

12. In a cigar making machine, the combination of a hopper comprising a stationary circular base having a discharge passage opening through the top and the peripheral face thereof, a cylindrical wall having the lower portion thereof skirting the peripheral face of the base and closing the exit end of the discharge passage, said wall being revoluble about the axis of the base and having an opening in the portion thereof skirting the base, for registering with the exit end of such discharge passage, a plurality of arms fixed to the inner face of the cylindrical wall and movable successively above the inlet of the discharge passage in a plane intersecting a line coincident with the axis of said inlet and thereby forcing material into position to move into the discharge passage, one of the arms serving as a closure for said inlet, and a stationary agitator supported outside of the cylindrical wall and projecting from the top thereof downwardly within the same and terminating above the path of the plurality of arms, and mechanism for rotating the cylindrical wall, substantially as set forth.

13. In a cigar making machine, the combination of a frame provided with an upright bearing, a circular base fixed to the upper end of the bearing and concentric therewith, said base having a discharge passage, a revoluble member journaled in the bearing, a cylindrical wall concentric with the base and fixed to the upper end of the revoluble member, said wall having means for controlling the exit of material from the discharge passage, and means connected to the lower end of the revoluble member for rotating the same.

14. In a cigar making machine, the combination of a frame provided with a top plate, and an upright bearing rising from the top plate, a circular base fixed to the upper end of the bearing and concentric

therewith, said base having a discharge passage opening through the top and the peripheral face thereof, a revoluble member journaled in the bearing, a cylindrical wall concentric with the base and having the lower portion thereof skirting the peripheral face of the base and closing the exit end of the discharge passage, said wall having an opening in the portion thereof skirting the base, for registering with the exit end of such discharge passage, a plurality of arms fixed to the upper end of the revoluble member and to the cylindrical wall and movable successively above the inlet of the discharge passage in a plane intersecting a line coincident with the axis of said inlet and thereby forcing material into position to move into the discharge passage, one of the arms serving as a closure for said inlet, and means beneath the top plate connected to the lower end of the revoluble member for rotating the same, substantially as set forth.

15. In a cigar making machine, the combination of rolling mechanism, a filler conveyor comprising means having a guide passage for the filler, and a plunger device for moving the filler in the passage, the plunger device including two sections, one operating to engage the filler and being a driven section, and the other being a driving section, yielding means coacting with said sections for transmitting movement of the driving section to the driven section, and for permitting the driving section to move relatively to the driven section after the driven section has been moved a predetermined distance, and means independent of the yielding means and coacting with said sections for returning the driven section with the driving section, and means for operating said driving section, substantially as described.

16. In a cigar making machine, the combination of rolling mechanism, a filler conveyor comprising means having a guide passage for the filler, and a plunger device for moving the filler in the passage, the plunger device including two sections, one operating to engage the filler, and one being movable relatively to the other, a spring normally tending to move one of the sections relatively to the other, and means independent of the spring for limiting the movement of said one of the sections relatively to the other, and means for operating the plunger device, substantially as set forth.

17. In a cigar making machine, the combination of rolling mechanism, a filler conveyor comprising means having a guide passage for the filler, and a plunger device for forcing the filler from the passage, the plunger device including two sections, one operating to engage the filler and being a driven section, and the other being a driving section, yielding means coacting with said

sections for transmitting movement of the driving section to the driven section, and for permitting the driving section to move relatively to the driven section after the driven section has been moved a predetermined distance, and for permitting the driving section to return a predetermined distance independently of the driven section, and rigid means coacting with said sections for returning the driven section with the driving section after the driving section has returned a predetermined distance independently of the driven section, and means for operating said driving section, substantially as described.

18. In a cigar making machine, the combination of rolling mechanism, a filler conveyor comprising a movable support, a guide passage for the filler carried by the support, and a plunger movable in the passage, and actuating means for the support and the plunger, said means comprising a single movable member and connections from said member to the support and to the plunger, for positively moving the support and the plunger together toward the rolling mechanism for a limited distance and for thereafter moving the plunger toward the rolling mechanism relatively to the support for an additional distance and permitting the support to remain at rest during the additional movement of the plunger, substantially as described.

19. In a cigar making machine, the combination of rolling mechanism, a filler conveyor comprising a movable support, a guide passage for the filler carried by the support, and a plunger movable in the passage, and actuating means for the support and the plunger, said means comprising a single movable member and connections from said member to the support and to the plunger, for positively moving the support and the plunger together toward the rolling mechanism for a limited distance and for thereafter moving the plunger toward the rolling mechanism relatively to the support for an additional distance and permitting the support to remain at rest during the additional movement of the plunger, the connections to the support comprising two members detachably and yieldingly engaging each other and being out of engagement with each other during the additional movement of the plunger for permitting the support to remain stationary relatively to the plunger during said additional movement of the plunger, substantially as described.

20. In a cigar making machine, the combination of rolling mechanism, a filler conveyor comprising a movable support, a guide passage for the filler carried by the support, and a plunger device for moving the filler in the passage and including advance

and rear sections, a yielding connection between the sections, and means for normally coupling the sections together and permitting a limited movement thereof relatively to each other, and actuating means for moving the plunger device and the support as a body and for moving one of said sections relatively to the other, substantially as described.

10 21. In a cigar making machine, the combination of rolling mechanism, a filler conveyor comprising a chute for the filler, and a plunger device for moving the filler in the chute, the plunger device comprising a
15 movable member, and the chute being movable toward the rolling mechanism relatively to said movable member, and means for connecting the chute to said movable member to effect the return of the chute
20 with said member and for releasing the chute to permit it to move toward the rolling mechanism independently of said member, and means for actuating the plunger device, substantially as described.

25 22. In a cigar making machine, the combination of rolling mechanism, a filler conveyor comprising a chute for the filler, and a plunger device for moving the filler in the chute, the plunger device comprising
30 two sections, one operating to engage the filler and the other having a limited movement from the rolling mechanism relatively to the section engaging the filler, and the chute being movable toward the rolling
35 mechanism relatively to the plunger device and being movable a limited distance from the rolling mechanism relatively to the section of the plunger device engaging the filler, and means for connecting the chute to
40 the plunger device to effect the return of the chute from the rolling mechanism and for releasing the chute to move toward the rolling mechanism independently of said plunger device, and means for actuating the
45 plunger device, substantially as described.

23. In a cigar making machine, the combination of rolling mechanism, a filler conveyor comprising a chute for the filler, and a plunger device for moving the filler in the chute, the plunger device comprising two sections, one operating to engage the filler and the other having a limited return movement from the rolling mechanism relatively to the section engaging the filler, and a spring coacting with the sections of the plunger device during the limited return movement of said one of the sections relatively to the section engaging the filler, and the chute being movable toward the rolling mechanism relatively to the plunger device and being movable a limited distance from the rolling mechanism relatively to the section of the plunger device engaging the filler, and means for connecting the chute to the plunger device to effect the return of

the chute from the rolling mechanism, and for releasing the chute to move toward the rolling mechanism independently of said plunger device, and means for actuating the plunger device, substantially as described.

24. In a cigar making machine, the combination of rolling mechanism, a filler conveyer comprising a chute for the filler, and a plunger device for moving the filler in the chute, the plunger device comprising two sections, one operating to engage the filler and the other having a limited return movement from the rolling mechanism relatively to the section engaging the filler, a spring coacting with the sections of the plunger device during the limited return movement of said one of the sections relatively to the section engaging the filler, and means coacting with said sections to return both sections from the rolling mechanism together after the limited return movement of said one of the sections, and the chute being movable toward the rolling mechanism relatively to the plunger device and being movable a limited distance from the rolling mechanism relatively to the section of the plunger device engaging the filler, and means for connecting the chute to the plunger device to effect the return of the chute from the rolling mechanism, and for releasing the chute to move toward the rolling mechanism independently of said plunger device, and means for actuating the plunger device, substantially as described. 75 80 85 90 95

25. In a cigar making machine, the combination of rolling mechanism, a filler conveyor comprising a chute for the filler, and a plunger device for moving the filler in the chute, the plunger device comprising two sections, one operating to engage the filler and the other having a limited return movement from the rolling mechanism relatively to the section engaging the filler, a spring coacting with the sections of the plunger device during the limited return movement of said one of the sections relatively to the section engaging the filler, and means coacting with said sections to return both sections from the rolling mechanism together after the limited return movement of said one of the sections, and the chute being movable toward the rolling mechanism relatively to the plunger device and being movable a limited distance from the rolling mechanism with the section not engaging the filler and relatively to said section engaging the filler, and means for connecting the chute to said section not engaging the filler, and for releasing the chute from said section to move toward the rolling mechanism independently of said plunger device, and means for actuating the plunger device, substantially as described. 100

26. In a cigar making machine, the combination of rolling mechanism, a filler con- 130

veyer comprising a chute for the filler, and a plunger device for moving the filler in the chute, the plunger device including two sections, one operating to engage the filler and 5 being a driven section, and the other being a driving section, yielding means coacting with said sections for transmitting movement of the driving section to the driven section and for permitting the driving section 10 to move in reverse directions for a limited distance relatively to the driven section after the driven section has been moved a predetermined distance, and the chute being movable toward the rolling mechanism relatively 15 to said sections of the plunger device, and means for connecting the chute and the driving section of the plunger device, said means releasing the chute to permit it to move toward the rolling mechanism relatively to the 20 plunger device, and said means serving to operatively connect the chute and the driving section before said section reaches the limit of its movement from the rolling mechanism relatively to the driven section 25 of the plunger device and thereby causing the chute to move from the rolling mechanism relatively to said driven section, and means for operating the driving section of the plunger device, substantially as described. 30

27. In a cigar making machine, the combination of rolling mechanism, a filler conveyor comprising a chute for the filler, and a plunger device for moving the filler in the 35 chute, the plunger device comprising two sections, one operating to engage the filler, and one being movable relatively to the other, yielding means normally tending to move one of the sections relatively to the 40 other, and means for limiting the movement of said one of the sections relatively to the other, and the chute being movable toward the rolling mechanism relatively to said sections of the plunger device, and means for 45 connecting the chute to the section of the plunger device not engaging the filler, and for releasing the chute from said section, and means for actuating the plunger device, substantially as described.

50 28. In a cigar making machine, the combination of rolling mechanism, a filler conveyor comprising a chute for the filler, and a plunger device for moving the filler in the chute, the plunger device including two sections, one operating to engage the filler and 55 being a driven section, and the other being a driving section, yielding means coacting with said sections for transmitting movement of the driving section to the driven 60 section and for permitting the driving section to move relatively to the driven section after the driven section has been moved a predetermined distance, and means independent of the yielding means and coacting with said sections of the plunger device for

returning the driven section with the driving section after the latter section has moved from the rolling mechanism a limited distance relatively to the driven section, and the chute being movable toward the rolling 70 mechanism relatively to said sections of the plunger device, and means for connecting the chute and the driving section of the plunger device, said means releasing the chute to permit it to move toward the rolling 75 mechanism relatively to the plunger device, and said means serving to operatively connect the chute and the driving section before said section reaches the limit of its movement from the rolling mechanism relatively to the driven section of the plunger device and thereby causing the chute to move from the rolling mechanism relatively to said driven section, and means for operating the driving section of the plunger device, substantially as described. 80

29. In a cigar making machine, the combination of rolling mechanism, a filler conveyor comprising a chute for the filler, and a plunger device for moving the filler in the 90 chute, the plunger device comprising two sections, one operating to engage the filler, and one being movable relatively to the other, a spring normally tending to move one of the sections relatively to the other, 95 and means independent of the spring for limiting the movement of said one of the sections relatively to the other, and the chute being movable toward the rolling mechanism relatively to said sections of the plunger device, and means for connecting the chute to the section of the plunger device not engaging the filler, and for releasing the chute from said section, and means for actuating the plunger device, substantially 100 as described. 105

30. In a cigar making machine, the combination of rolling mechanism, a filler conveyor comprising a chute for the filler, and a plunger device for moving the filler in the 110 chute, the plunger device comprising two sections, one operating to engage the filler, and one being movable relatively to the other, yielding means normally tending to move one of the sections relatively to the other, rigid means independent of the yielding means for limiting the movement of said one of the sections relatively to the other, and the chute being movable toward the rolling mechanism relatively to said sections of the plunger device, and means for connecting the chute to the section of the plunger device not engaging the filler, and for releasing the chute from said section, 115 and means for actuating the plunger device, substantially as set forth. 120

31. In a cigar making machine, the combination of rolling mechanism, a filler conveyor comprising a chute for the filler, and a plunger movable in the chute, the plunger 130

normally closing the exit of the chute for preventing the premature discharge of the 5 filler from said exit, the chute and the plunger being movable together toward the rolling mechanism for a limited distance after the entrance of the material into the chute, and the chute then being movable toward the rolling mechanism relatively to the plunger for effecting the feed of the filler in advance of the plunger, and means for effecting the movement of the chute and the plunger, substantially as described.

32. In a cigar making machine, the combination of rolling mechanism, a filler conveyor comprising a chute for the filler, said chute being movable about an axis relatively to the rolling mechanism, and a plunger movable about said axis with the chute, and movable rectilinearly relatively to the 15 chute, said chute being also movable rectilinearly relatively to the plunger for effecting the feed of the filler in advance of the plunger, and actuating means for the filler conveyor, substantially as set forth.

33. In a cigar making machine, the combination of rolling mechanism, a filler conveyor comprising a chute for the filler, and a plunger movable in the chute, the plunger normally closing the exit of the chute for preventing the premature discharge of the 30 filler from said exit, the chute and the plunger being movable together about an axis for a limited distance after the entrance of the material into the chute, the chute being thereafter movable in a straight line relatively to the plunger for effecting the feed of the filler in advance of the plunger, and the plunger being thereafter movable in the chute relatively thereto to deliver the filler 35 to the rolling mechanism, and means for effecting the movement of the chute and the plunger, substantially as set forth.

34. In a cigar making machine, the combination of rolling mechanism, a filler conveyor comprising two parts, one being a chute for the filler and the other being a plunger, one of said parts being movable relatively to the other, and both of said 45 parts being movable as a unit together, and means for detachably connecting said parts, said means being movable out of operative position for permitting the relative movement of said one of the parts and being movable into operative position for causing both of said parts to move together, and actuating means for the filler conveyor, substantially as described.

35. In a cigar making machine, the combination of rolling mechanism, a filler conveyor comprising two parts, one being a chute for the filler, and the other being a plunger movable in the chute, the plunger normally closing the exit of the chute for preventing the premature discharge of the 50 filler from the exit, and the chute being movable relatively to the plunger for effecting the feed of the filler in advance of the plunger, and means for detachably connecting one of said parts to the other when the plunger is in its depressed position, to cause the 55 chute to return with the plunger, means for actuating the first mentioned means to release the chute and permit it to move relatively to the plunger, and means for actuating the plunger, substantially as described.

36. In a cigar making machine, the combination of rolling mechanism, a filler conveyor comprising two parts, one being a chute for the filler and the other being a plunger, one of said parts being movable relatively to the other and both of said 60 parts being movable as a unit together, and means carried by one of the said parts and detachably engaging the other part, said means being movable out of operative position for permitting the relative movement of said one of the parts and being movable into operative position for causing both of 65 said parts to move together, and actuating means for the plunger, substantially as described.

37. In a cigar making machine, the combination of rolling mechanism, a filler conveyor comprising two parts, one being a chute for the filler and the other being a plunger, each of said parts being movable relatively to the other and both of said 70 parts being movable together about an axis, and means for detachably connecting said parts, said means being movable out of operative position for permitting the relative movement of said parts, and being movable into 75 operative position for causing both of said parts to move together, and actuating means for the filler conveyor, substantially as described.

38. In a cigar making machine, the combination of rolling mechanism, a filler conveyor comprising two parts, one being a movable chute for the filler and the other being a plunger movable in the chute, one of said parts of the filler conveyor being also movable relatively to the other, means carried by one of said parts of the filler conveyor for detachably locking said parts together, and an abutment for forcing said 80 means from operative position, and actuating means for the filler conveyor, substantially 85 as described.

39. In a cigar making machine, the combination of rolling mechanism, a filler conveyor comprising two parts, one being a movable chute for the filler and the other being a plunger movable in the chute, said 90 chute and plunger being also movable relatively to each other, means carried by one of said parts of the filler conveyor for lock- 95

ing said parts together, and an abutment for forcing said means from operative position, and actuating means for the filler conveyer, substantially as set forth.

5 40. In a cigar making machine, the combination of rolling mechanism, a filler conveyer comprising two parts, one being a movable chute for the filler and the other being a plunger movable in the chute, one 10 of said parts of the filler conveyer being also movable relatively to the other, a catch pivoted to one of said parts and coacting with the other part for locking said parts together, means for holding the catch in operative position, and an abutment for forcing the catch from operative position, and actuating means for the filler conveyer, substantially as described. 15 70

20 41. In a cigar making machine, the combination of rolling mechanism, a filler conveyer comprising a movable chute for the filler, a plunger movable in the chute, a catch pivoted to the plunger and coacting with the chute for locking the chute and the plunger together, and an abutment for coacting with the catch to force the same from operative position, and actuating means for the filler conveyer, substantially as described. 25 80

25 42. In a cigar making machine, the combination of rolling mechanism, a filler conveyer comprising two parts, one a chute for the filler and the other a plunger, and actuating means including a friction device for moving one of the parts of the filler conveyer, said means comprising two members detachably and frictionally engaging each other, one member being movable with one of said parts of the filler conveyer, and the other member being movable with the other 40 of said parts of the filler conveyer, substantially as set forth. 90

30 43. In a cigar making machine, the combination of rolling mechanism, a filler conveyer comprising two parts, one a chute for the filler and the other a plunger, and actuating means including a friction device for moving one of the parts of the filler conveyer, said means comprising two members detachably and frictionally engaging each 45 other, one member being movable with one of said parts of the filler conveyer, and the other member being movable with the other of said parts of the filler conveyer, said members being detachable from each other 50 100

55 upon a predetermined movement of said one of the parts of the filler conveyer, substantially as described. 105

60 44. In a cigar making machine, the combination of rolling mechanism, a filler conveyer comprising a movable chute for the filler, a plunger movable toward the rolling mechanism with the chute for a limited distance, said chute and plunger being also movable relatively to each other, actuating 110

means connected to the plunger, and connections between said actuating means and the chute, said connections including a lost motion friction device for effecting movement of the chute toward the rolling mechanism with the plunger, substantially as described. 115 65

45. In a cigar making machine, the combination of rolling mechanism, a filler conveyer comprising a support formed with a guide, a chute mounted on the support, a plunger movable in the chute and normally arranged to close the chute from prematurely discharging the filler, the chute normally tending to move along the guide of the support relatively to the plunger into position to permit the feed of the filler in advance of the plunger, and actuating mechanism for the support, the chute and the plunger, said actuating mechanism including means for moving the support, the chute and the plunger as one body toward the 120 85 rolling mechanism, and for thereafter permitting the chute to move toward the rolling mechanism relatively to the support and the plunger, and for then moving the plunger toward the rolling mechanism independently 90 of the support and the chute after said independent movement of the chute, substantially as set forth. 95

46. In a cigar making machine, the combination of rolling mechanism, a filler conveyer comprising a support formed with a guide, a chute mounted on the support, a plunger movable in the chute and normally arranged to close the chute from prematurely discharging the filler, the chute normally tending to move along the guide of the support relatively to the plunger into position to permit the feed of the filler in advance of the plunger, means for normally connecting the plunger and the chute, and means for releasing the first mentioned means prior to the movement of the plunger in the chute, and means for actuating the plunger, substantially as set forth. 100 105

47. In a cigar making machine, the combination of rolling mechanism, a filler conveyer comprising a support movable about an axis relatively to the rolling mechanism, a chute for the filler, said chute being movable about said axis with the support, and a plunger movable in the chute, and actuating means for the filler conveyer, said means including a member carried by the support and a member movable with the plunger and frictionally and detachably engaging the first-mentioned member, substantially as set forth. 110 115

48. In a cigar making machine, the combination of rolling mechanism, a filler conveyer comprising a chute for the filler, and a plunger, and actuating means including a cam, a pivoted lever having one end coacting with the cam, and its other end provided with teeth, and a rocking arm having teeth 120 125

coacting with the first-mentioned teeth, said arm being connected to the filler conveyer, substantially as described.

49. In a cigar making machine, the combination of rolling mechanism comprising a movable member, an apron operated by the movable member, said apron forming a loop for receiving the material to be rolled, and rollers for the apron, one of the rollers co-operating with the apron to close the open side of the loop after the entrance of the material, and the other roller being movable relatively to the first mentioned roller upon each operation of the movable member for tightening the loop around said material, and actuating means for said member and said one of the rollers, substantially as described.

50. In a cigar making machine, the combination of rolling mechanism comprising a movable member, an apron operated by the movable member, said apron forming a loop for receiving the material to be rolled, a roller for coöperating with the apron to close the open side of the loop after the entrance of the material, a support for the roller movable relatively to the path of the movable member, a spring coacting with the support to normally tend to move the roller away from said path, adjustable means for limiting the movement of the support by the spring, and a second roller coöperating with the apron and movable relatively to the first mentioned roller upon each operation of the movable member for tightening the loop around said material, and actuating means for said member and the second mentioned roller, substantially as described.

51. In a cigar making machine, the combination of rolling mechanism comprising a movable member, an apron operated by the movable member, said apron forming a loop for receiving the material to be rolled, and rollers for the apron, one of the rollers being adjustable relatively to the path of the movable member, and the other roller being movable upon each operation of the movable member for tightening the loop, and actuating means for said member and the second-mentioned roller, substantially as described.

52. In a cigar making machine, the combination of rolling mechanism comprising a movable member, an apron operated by the movable member, said apron forming a loop for receiving the material to be rolled, rollers for the apron, and supports for the rollers, said supports being pivoted on a common axis and movable independently of each other, one of the supports being adjustable relatively to the apron, and the other support being movable upon each operation of the movable member, and actuating means for said member and said other support, substantially as described.

53. In a cigar making machine, the combi-

nation of two elements, one a rolling mechanism and the other a wrapper-controller, one of said elements being movable in one direction during the operation of said mechanism in rolling a part of the wrapper about the bunch, and being movable in another direction during the operation of said mechanism in rolling a remaining portion of the wrapper about the bunch, and actuating means for the relatively movable element, substantially as described.

54. In a cigar making machine, the combination of two elements, one a rolling mechanism and the other a wrapper-controller, one of said elements being movable in one direction during the operation of said mechanism in rolling a part of the wrapper about the bunch, and being movable about a pivot in another direction during the operation of said mechanism in rolling a remaining portion of the wrapper about the bunch, and actuating means for the relatively movable element, substantially as described.

55. In a cigar making machine, the combination of rolling mechanism, a wrapper-controller movable in one direction relatively to a portion of the rolling mechanism during the operation of said mechanism in rolling a part of the wrapper about the bunch, and movable in another direction about a pivot relatively to said mechanism during the operation of said mechanism in rolling a remaining portion of the wrapper about the bunch, and actuating means for the wrapper-controller, substantially as described.

56. In a cigar making machine, the combination of rolling mechanism, a wrapper-controller movable in one direction about a pivot during the operation of said mechanism in rolling a part of the wrapper about the bunch, and movable in another direction about a second pivot during the operation of said mechanism in rolling a remaining portion of the wrapper about the bunch, said pivots being arranged at an angle to each other, and actuating means for the wrapper-controller, substantially as described.

57. In a cigar making machine, the combination of rolling mechanism comprising a movable member, and an apron operated by the movable member, a wrapper-controller movable with the movable member during the operation of said mechanism in rolling a part of the wrapper about the bunch and movable relatively to said member during the operation of said mechanism in rolling a remaining portion of the wrapper about the bunch, and actuating means for the movable member and the wrapper-controller, substantially as described.

58. In a cigar making machine, the combination of rolling mechanism comprising a pivoted member, and an apron operated by

the pivoted member, a wrapper-controller movable about the pivot of the member during the operation of said mechanism in rolling a part of the wrapper about the bunch, 5 and movable about a second pivot relatively to said mechanism during the operation of said mechanism in rolling a remaining portion of the wrapper about the bunch, and actuating means for the pivoted member and the wrapper-controller, substantially as described.

59. In a cigar making machine, the combination of rolling mechanism comprising a movable member, an apron operated by the 15 movable member, and means on which the apron is movable, said member being movable relatively to said means, a wrapper-controller movable with the member during the operation of said mechanism in rolling a 20 part of the wrapper about the bunch, and movable about a pivot relatively to the member during the operation of said mechanism in rolling a remaining portion of the wrapper about the bunch, and actuating means 25 for the movable member and the wrapper-controller, substantially as described.

60. In a cigar making machine, the combination of rolling mechanism comprising a pivoted member, an apron operated by the 30 pivoted member, and means on which the apron is movable, said member being movable about its pivot relatively to said means, a wrapper-controller movable about said pivot with the pivoted member during the 35 operation of said mechanism in rolling a part of the wrapper about the bunch, and movable about a second pivot relatively to the pivoted member during the operation of said mechanism in rolling a remaining portion 40 of the wrapper about the bunch, said pivots being arranged at an angle to each other, and actuating means for the pivoted member and the wrapper-controller, substantially as described.

45 61. In a cigar making machine, the combination of rolling mechanism comprising a movable member, a wrapper-controller, a connection between the movable member and the wrapper-controller for causing said parts 50 to move together, a stop for limiting the movement of the wrapper-controller with the movable member before the wrapper has been completely rolled about the bunch, and actuating means for said member and for 55 moving the wrapper-controller relatively to said member during the rolling of the finally wound portion of the wrapper about the bunch, substantially as described.

60 62. In a cigar making machine, the combination of rolling mechanism comprising a movable member, a wrapper-controller, a friction device between the movable member and the wrapper controller for causing said parts to move together, a stop for limiting

the movement of the wrapper-controller 65 with the movable member, and actuating means for said member, substantially as described.

63. In a cigar making machine, the combination of rolling mechanism comprising a 70 member movable to and fro, a wrapper-controller, a friction device between the movable member and the wrapper-controller for causing said parts to move together, stops for limiting the movement of the wrapper-controller 75 in opposite directions with the movable member, and actuating means for said member, substantially as described.

64. In a cigar making machine, the combination of rolling mechanism comprising a 80 movable member, a pivoted wrapper-controller, a connection between the movable member and the wrapper-controller for causing said wrapper-controller to rock on its pivot, and actuating means for said member, 85 substantially as described.

65. In a cigar making machine, the combination of rolling mechanism comprising a member movable to and fro, a pivoted wrapper-controller, a friction device between the 90 movable member and the wrapper-controller for causing said wrapper-controller to rock on its pivot, stops for limiting the movement of the wrapper-controller in opposite directions, and actuating means for said member, 95 substantially as described.

66. In a cigar-making machine, the combination of rolling mechanism comprising a movable member, a pivoted wrapper-controller having its axis disposed at an angle 100 to the direction of movement of the movable member, means between the movable member and the wrapper-controller for causing said wrapper-controller to rock on its pivot relatively to the movable member, and actuating means for said member, 105 substantially as described.

67. In a cigar making machine, the combination of rolling mechanism comprising a movable member, a wrapper-controller, a 110 connection between the movable member and the wrapper-controller for causing said parts to move together during the winding about the bunch of the initially wound portion of the wrapper, a stop for limiting the movement of the wrapper-controller with the movable member, a second connection 115 between the movable member and the wrapper-controller for causing said wrapper-controller to move relatively to the movable member during the winding about the bunch of a remaining portion of the wrapper, a stop for limiting the second-mentioned movement of the wrapper-controller, and actuating means for said member, substantially 120 as described.

68. In a cigar making machine, the combination of rolling mechanism comprising a

- member moving to and fro, a pivoted wrapper-controller, a friction device between the movable member and the wrapper-controller for causing said parts to move together, 5 stops for limiting the movement of the wrapper-controller in opposite directions with the movable member, a friction device between the movable member and the wrapper-controller for causing said wrapper-controller 10 to move on its pivot relatively to the movable member, stops for limiting the second-mentioned movement of the wrapper-controller in opposite directions, and actuating means for said member, substantially as described.
69. In a cigar making machine, the combination of rolling mechanism, a wrapper-controller including a tension roller and coacting means for engaging opposite sides of 20 the wrapper, said wrapper-controller being movable in a plurality of directions disposed at an angle to each other, and actuating means for the wrapper-controller, substantially as described.
70. In a cigar making machine, the combination of rolling mechanism and a wrapper-controller including tension rollers for engaging opposite sides of the wrapper, substantially as described.
71. In a cigar making machine, the combination of rolling mechanism, a wrapper-controller including tension rollers for engaging opposite sides of the wrapper, said wrapper-controller being movable in a plurality of directions disposed at an angle to each other, and actuating means for the wrapper-controller, substantially as described.
72. In a cigar making machine, the combination of rolling mechanism, a wrapper-controller including a tension member out of contact with the parts of the rolling mechanism which are movable to roll the wrapper about the bunch, and means for automatically moving the tension member into and out of its position assumed when engaging the wrapper, substantially as described.
73. In a cigar making machine, the combination of rolling mechanism, a wrapper-controller including a tension member, means for automatically moving the tension member out of its position assumed when engaging the wrapper, and a filler conveyer for supplying the filler to the rolling mechanism and for forcing the tension member to its position assumed when engaging the wrapper, substantially as described.
74. In a cigar making machine, the combination of rolling mechanism, a wrapper-controller including a tension roller for engaging the wrapper, means for moving the tension roller out of position to engage the wrapper, and means for moving the tension roller in the reverse direction, substantially as described.

75. In a cigar making machine, the combination of rolling mechanism, a wrapper-controller including tension members for engaging opposite sides of the wrapper, one of said members being movable into and out of operative position, and means for moving said one of the tension members, substantially as described.

76. In a cigar making machine, the combination of rolling mechanism, a wrapper-controller including a tension member for engaging the wrapper, a locking member for holding the tension member in operative position, means for forcing the locking member from operative position, and means for moving the tension member into and out of operative position, substantially as described.

77. In a cigar making machine, the combination of rolling mechanism, a wrapper-controller including a tension member for engaging the wrapper, a locking member movable automatically for holding the tension member in operative position, means for forcing the locking member from operative position, and means for moving the tension member into and out of operative position, substantially as described.

78. In a cigar making machine, the combination of rolling mechanism, a wrapper-controller including tension rollers for engaging opposite sides of the wrapper, one of the rollers being movable into and out of operative position, a locking member for holding said one of the rollers in operative position, means for forcing the locking member from operative position, and means for moving said one of the rollers into and out of operative position, substantially as described.

79. In a cigar making machine, the combination of rolling mechanism, a wrapper-controller including a tension member for engaging the wrapper, and a guide member for the wrapper arranged substantially parallel with the tension member and between said tension member and the contiguous moving surface of the rolling mechanism, substantially as described.

80. In a cigar making machine, the combination of rolling mechanism comprising an apron forming a loop, a wrapper controller including tension members for engaging the wrapper, and a member for guiding the wrapper when passing between the tension members and the loop, said member being arranged in the angle formed by portions of the apron converging toward each other at the loop and merging with the portions of the apron forming the opposite sides of the loop, and said member preventing the wrapper from engaging one of said converging portions of the apron, substantially as described.

81. In a cigar making machine, the combi-

5 nation of rolling mechanism comprising an apron forming a loop, a wrapper-controller including tension members for engaging opposite sides of the wrapper, and a member substantially parallel with the tension members for guiding the wrapper when passing between the tension members and the loop, substantially as described.

10 82. In a cigar making machine, the combination of rolling mechanism, a wrapper-controller including tension rollers for engaging opposite sides of the wrapper, and a guide member for the wrapper arranged substantially parallel with the tension rollers and guiding the wrapper between the tension rollers and the contiguous moving surface of the rolling mechanism, substantially as described.

15 83. In a cigar making machine, the combination of rolling mechanism, a wrapper-controller including tension rollers for engaging opposite sides of the wrapper, and a guide member consisting of a roller arranged between the tension rollers and the contiguous moving surface of the rolling mechanism for guiding the wrapper when passing from the tension rollers to the rolling mechanism, substantially as described.

20 84. In a cigar making machine, the combination of rolling mechanism comprising an apron forming a loop, a wrapper-controller including tension rollers for engaging opposite sides of the wrapper, and a guide roller arranged in the angle formed by portions of the apron converging toward each other at the loop and merging with the portions of the apron forming the opposite sides of the loop, said guide roller guiding the wrapper and preventing the same from 25 engaging one of said converging portion of the apron, substantially as described.

30 85. In a cigar making machine, the combination of rolling mechanism comprising an apron forming a loop, a wrapper-controller including tension members for engaging opposite sides of the wrapper, one of the tension members being movable into and out of operative position, means for moving said one of the tension members, and a member 35 for guiding the wrapper when passing between the tension members and the loop, said last-mentioned member being movable with said one of the tension members into and out of operative position, substantially 40 as described.

35 86. In a cigar making machine, the combination of rolling mechanism, a wrapper-controller including tension rollers for engaging opposite sides of the wrapper, one of the 45 rollers being movable into and out of operative position, means for moving said one of the tension rollers, and a guide roller movable with said one of the tension rollers into and out of operative position, said 50 60 65 guide roller guiding the wrapper in the

passage from the tension rollers to the contiguous moving surface of the rolling mechanism, substantially as described.

87. In a cigar making machine, the combination of a rolling mechanism, a wrapper-controller for controlling the movement of the wrapper when being wound about the bunch by the rolling mechanism, and a filler conveyor for supplying the filler to the rolling mechanism, said filler conveyor including means for controlling the operation of the wrapper-controller, substantially as described. 70 75

88. In a cigar making machine, the combination of rolling mechanism comprising an apron forming a loop for receiving the binder and the material to be rolled, means for moving the outer portion of the binder across the open side of the loop, and actuating means for the rolling mechanism and the first-mentioned means, substantially as described. 80 85

89. In a cigar making machine, the combination of rolling mechanism comprising a movable member, and an apron fixed to the movable member and operated thereby, said apron forming a loop for receiving the binder and the material to be rolled, means for moving the outer portion of the binder across the open side of the loop, said means being operated by the movable member, and actuating means for said member, substantially as described. 90 95

90. In a cigar making machine, the combination of a frame, rolling mechanism comprising a movable member, and an apron operated by the movable member, said apron forming a loop for receiving the binder and the material to be rolled, means pivoted to the frame for moving the outer portion 100 105 of the binder across the open side of the loop, said means being operated by the movable member, and actuating means for said member, substantially as described.

91. In a cigar making machine, the combination of rolling mechanism comprising a movable member, and an apron operated by the movable member, said apron forming a loop for receiving the binder and the material to be rolled, means for moving the outer portion of the binder across the open side of the loop, said means being frictionally connected to the movable member and operated thereby, and actuating means for said member, substantially as described. 110 115 120

92. In a cigar making machine, the combination of a frame, rolling mechanism comprising a movable member, an apron operated by the movable member, said apron forming a loop for receiving the binder and the material to be rolled, means pivoted to the frame for moving the outer portion of the binder across the open side of the loop, said means being frictionally connected to the movable member and operated thereby, 125 130

and actuating means for said member, substantially as described.

93. In a cigar making machine, mechanism for rolling the binder and the wrapper about the filler, and mechanism for engaging the wrapper independently of the binder and controlling the rolling of the wrapper by the first-mentioned mechanism, substantially as described.

- 10 94. In a cigar making machine, mechanism for simultaneously rolling the binder and the wrapper about the filler, and mechanism for engaging opposite sides of the wrapper independently of the binder and controlling the rolling of the wrapper by the first-mentioned mechanism, substantially as described.

- 15 95. In a cigar making machine, means for supplying the filler, mechanism for rolling the binder and the wrapper about the filler, and mechanism for engaging the wrapper independently of the binder and controlling the rolling of the wrapper by the first-mentioned mechanism, substantially as described,

- 20 96. In a cigar making machine, the combination of two elements, one a rolling mechanism comprising a flexible member forming a loop, and the other including a wrapper-controller for engaging the wrapper independently of the binder and controlling the rolling of the wrapper by the first-mentioned mechanism, said elements coacting to roll the binder and wrapper about the filler, substantially as described.

- 25 97. In a cigar making machine, mechanism for rolling the binder and the wrapper about the filler, and means for moving a portion of the binder independently of the wrapper, substantially as described.

- 30 98. In a cigar making machine, the combination of two elements, one a rolling mechanism comprising a flexible member forming

a loop, and the other including a binder-engaging means and a wrapper-controller, the binder-engaging means engaging the binder independently of the wrapper, and the wrapper-controller engaging the wrapper independently of the binder, said elements coacting to roll the binder and the 50 wrapper about the filler, substantially as described.

99. In a cigar making machine, the combination of rolling mechanism comprising a flexible member forming a loop, means for 55 moving the outer portion of the binder independently of the wrapper across the open side of the loop, and a wrapper-controller for engaging the wrapper independently of the binder, said roller mechanism, binder 60 moving means and wrapper-controller coacting to roll the binder about the filler and to roll the wrapper about the binder, substantially as described.

100. In a cigar making machine, the combination of a rolling mechanism comprising a flexible member forming a loop, the advance portion of the wrapper being supported on the flexible member and the binder upon said advance portion of the wrapper, 70 before the delivery of the filler, means for delivering the filler upon said binder, and means for engaging the rear end of the wrapper and controlling the wrapping thereof, substantially as described. 75

In testimony whereof, we have hereunto signed our names in the presence of two attesting witnesses, at Syracuse, in the county of Onondaga, in the State of New York, this 10th day of November, 1906.

WILLARD C. LIPE.
JOHN W. COUGHTRY.
